UNITED STATES PATENT OFFICE

111,453

DESIGN FOR A GLASS STOPPER

Everett F. Kelm, Corning, N. Y., assignor to
Corning Glass Works, Corning, N. Y., a cor-
poration of New York

Application July 21, 1938, Serial No. 78,640

Term of patent 14 years

To all whom it may concern:

Be it known that I, Everett F. Kelm, a citizen of the United States, residing at Corning, in the county of Steuben and State of New York, have invented a new, original, and ornamental Design for a Glass Stopper, of which the following is a specification, reference being had to the accompanying drawing, forming part thereof.

In the drawing, Fig. 1 is a front elevation of a

glass stopper showing my new design and Fig. 2 is a side elevation of the stopper showing particularly the configuration of the grip portion formed thereon.

I claim:

The ornamental design for a glass stopper, substantially as shown.

EVERETT F. KELM.
